UNITED STATES PATENT OFFICE.

ARTHUR ROLLASON, OF NEWCASTLE-ON-TYNE, COUNTY OF NORTHUMBERLAND, ENGLAND.

GAS OR CALORIC ENGINE.

SPECIFICATION forming part of Letters Patent No. 394,299, dated December 11, 1888.

Application filed June 2, 1888. Serial No. 275,875. (No model.) Patented in England March 7, 1888, No. 3,546.

To all whom it may concern:

Be it known that I, ARTHUR ROLLASON, a subject of the Queen of Great Britain and Ireland, residing at Newcastle-on-Tyne, in the county of Northumberland, England, have invented new and useful Improvements in and connected with Gas or Caloric Engines, of which the following is a specification.

Letters Patent for this invention have been granted in England on March 7, 1888, No. 3,546.

My invention relates to certain improvements in gas or vapor engines, and comprises constructional improvements in the appliances used in connection with such engines for the purpose of governing or controlling the gas or vapor admission and pressure in such a manner as more effectually to insure the most economical consumption of such gas or vapor at all times during working, and especially during variations of work and speed.

My invention consists in certain improved constructions and arrangements of fluid-admission and throttle valves and parts relating thereto, an improved construction of governor and connections or means for operating the said valves automatically to regulate the fluid-supply in exact accord with the work being done and the varying speeds of the motor.

The invention is illustrated in the drawings as applied to the combustion-chambers of a three-cycle gas-engine, but the improvements are applicable to all classes of gas, vapor, or other fluid-motor engines.

In the drawings, Figure 1 is a sectional plan of the engine combustion-chamber and one form of improved fluid-admission and throttle valves, the operating-gear being in plan. Fig. 2 is a side elevation of same, showing governor in section. Fig. 3 is a sectional plan of an alternative form of improved fluid-admission and throttle valves. Figs. 4 and 5 are cross-sections through the valve-casing and throttle-valves of Figs. 1 and 3, respectively; and Fig. 6 is a governor diagram, hereinafter explained. Fig. 7 is a back end elevation of engine embodying my improvements.

A is the compression and ignition chamber 50 fixed to and forming a prolongation of the engine-cylinder.

B is the slide-valve; C, the slide-valve cover.

a is the admission-port to compression-chamber and cylinder A. 55

a' is the air-admission port.

c is the gas-admission port, the admission of gaseous mixture from the ports a' and c being controlled by the three-way port b of the slide B. The operating connections to the 60 said slide B are not illustrated, forming no part of this invention. The slide-valve cover C is formed to contain the fluid-admission and throttle valves.

Referring to Fig. 1, d is a lift-valve, fitting 65 closely and held by a spring, d', against a seating, d'', formed in the valve-casing e. This casing is provided with slots e', as shown also in Fig. 4. Inclosed in the same casing e is the throttle-valve t, which is not attached to the 70 lift-valve d and does not touch the valve-casing e, thus being capable of moving very freely. It is also provided with wings and slots t', corresponding to those aforesaid, and secured to a spindle, f, capable of freely turning, and also horizontal or endwise movement in a long bearing, f', on the outer end of the casing and carrying on its outer end a sector, g.

This sector is operated by the movement of 80 the governor through the connections herein-after described. The gaseous fluid passes from the supply-pipe through a passage in the slide-valve cover and circulates round an annular passage, h. By the vibratory move- 85 ment of the throttle-valve t with the casing e the area of the openings e' t' is increased and diminished, thus varying the fluid-supply exactly as required by the engine. By the lon- 90 gitudinal or endwise movement of the throt- 90 tle-valve spindle f, abutting against its stem, the valve d is opened at the periods required and automatically reclosed by spring d'. In the alternative construction of this appliance (shown in Fig. 3) the fluid enters from the 95 cock k, and the throttle-valve is of the form of a disk, t, with portions t' cut away and capable of turning freely. It does not fit tightly

against the seating d^2 , in which corresponding holes, e' , for the passage of fluid are formed. The position of either of the throttle-valves described is regulated by the position of the governor through the medium of connecting-pieces and gear. (Shown in Figs. 1 and 2.) A pin, p , attached to the sector g , passes through a block, g' , sliding in the fork end of lever l , which is centered at l' on bracket l^2 , and has a sliding connection on the governor and rises and falls therewith, thus vibrating and partially closing or opening the throttle-valve t . The throttle-valve may be so adjusted that as the governor rises toward its top position the supply of gas or vapor is diminished until the mixture becomes diluted to a certain point, beyond which it is found economical to suppress ignitions altogether; or for steady work the throttle-valve may be regulated to control to any desired limit without suppressing any ignitions.

For the purpose of opening lift-valve d at the proper times, a lever, o , is centered on the bracket l^2 , fixed to the cylinder. Its lower end carries a roller, o' , which is actuated by a cam, g , on the engine counter-shaft. (See Fig. 7.) The lever o carries at its upper end a push-piece, o^2 , which, pressing on the end of sector g , imparts the endwise motion which lifts the valve d . Should the governor rise to its highest position, the sector is lifted clear of the push-piece o^2 , and the supply-valve d is not opened. On the other hand, if the governor should fall below its working position, a pin, l^3 , on lever l presses on one end of a lever, m , centered at m' on governor-bracket l^2 , and carrying at its other end an adjustable counter-weight, m^2 . Should the speed of the engine still continue to fall, the weight of the governor presses on the end of the lever m , raising the end carrying the counter-weight m^2 , and at the same time raising a pin, s , fixed on lever m off its seating in a catch, R , which, when the engine is working at its normal speed, supports lever and counter-weight m^2 . The continued downward pressure of the governor brings it to its lowest position, in which the top of the sector g is below the push-piece o^2 of lever o , and thus should the engine stop from any cause the fluid-admission valve d will not be lifted or remain open.

The pin s on lever m may be placed in a recess on catch R , in which case the catch no longer supports the counter-weight m^2 , and the latter, acting against the weight of the governor-body, will lower the speed of the engine more or less, according to its position on lever m . The engine will run at any speed within the limits of the governor that may be required, the position shown in Fig. 2 being for the highest speed with weighted cap on governor. The weighted lever m is supported by catch R .

To reduce the speed, the pin s may be put into another recess in catch R , when the other end will catch on the pin l^3 , thus reducing the

weight to be lifted by the descending governor. By moving the weight m^2 along the lever m the speed may thus be considerably varied.

The improved construction of governor is shown in sectional elevation in Fig. 2, and Fig. 6 is a diagram illustrating the various positions of arm and ball.

V is a heavy body with a loose cap, v , of suitable weight. w are arms carrying the usual balls. Each arm w is centered on a pin, v' , in a lug formed on spindle v^2 .

v^3 v^3 are oil-races. The upper surface of arm w is a portion of a circle, which preferably passes through the center of pin v' , on which the arm works. The circular portion of the arm bears against a flat surface, x , formed on the governor-body V , and as the arm turns on the pin v' the point of contact moves either toward or away from the center of spindle v^2 . By properly adjusting the angle which this flat surface x makes with the center of the spindle v^2 the arm w will roll upon this surface without any appreciable slipping. Fig. 6 is a diagram showing one arm in middle and extreme end positions. If the arm were to roll on this surface, the center of the pin v' would trace out a portion of a cycloid, PQ . The vertical line YZ is a tangent to this cycloid at the point v' . The points of contact of arms in three positions are $z' z z''$, and the moment of the weight of the body of the governor tending to turn the arm about the center of the pin v' are proportional to distances between the points $z' z z''$ and the line YZ . These distances may be made approximately proportional to the moment of the centrifugal force of the ball and arm about the same point, in which case the governor will be nearly isochronous, and may be made as sensitive as convenient by altering the curvature of the arm, the angle which the flat surface makes with the vertical line, and the distance of point y from the center line.

What I claim as my invention, and desire to secure by Letters Patent, is—

1. In a gas or calorific engine, the combination, with the compression and ignition chamber, cylinder, slide-valve, and air and gas admission ports, of slide-valve cover with gas-supply and annular passage h , a casing containing a spring return lift-valve, d , and adjustable vibratory throttle-valve, valve t , with projecting spindle f , said casing and throttle-valve being both provided with corresponding admission-ports, $e' t'$, and all arranged to operate substantially as set forth.

2. In a gas or calorific engine, the combination, with the compression-chamber, cylinder, slide-valve, air and gas admission ports, slide-valve cover and casing, with annular gas-passage h , and containing regulating spring return-lift, and adjustable vibratory throttle-valves d and t , and extended spindle f , constructed substantially as shown, of sector g , governor and intermediate connections, push-

- piece o^3 and lever o , operated by engine counter-shaft, all arranged substantially as set forth.
3. In a gas or calorie engine, the combination, with a slide-valve to which the fluid supply is controlled by a spring return lift-valve, and an adjustable vibratory throttle-valve constructed as specified, the throttle-valve vibrated by a governor and the lift-valve through connections by the engine counter-shaft, of the means, substantially as set forth, for varying the speed by varying the duty of said governor, consisting of levers l m and adjustable weight m^2 , pins r s , and catch R , arranged as set forth.
4. In a gas or calorie engine, the combination, with valve-casing C and valves d and t , spindle f , sector g , levers l and m , with pins p , s , and r , and adjustable weight m^2 , catch R , push-piece q , and lever o , of governor and engine counter-shaft carrying cammed wheel, all arranged and operating substantially as and for the purposes set forth.
5. In a gas-engine, the combination, with a gas-inlet valve provided with a stem and having a constant amount of lift or opening, of a spindle for lifting the valve, projecting through the valve-casing and operated periodically by the engine, and an oscillating throttle-valve secured to the said spindle behind the said inlet-valve and controlled by a speed-governor for varying the supply of gas.
6. In a gas-engine, the combination, with a lifting gas-inlet valve provided with a stem, 35 of an oscillating throttle-valve arranged behind the said inlet-valve, a spindle projecting through the valve-casing for lifting the inlet-valve and oscillating the throttle-valve, a sector upon the throttle-valve spindle, and a 40 speed-governor operatively connected with the end of said sector, thereby controlling the admission of gas through the throttle-valve and permitting the said sector and lifting-valve to be actuated by the engine at periodic intervals.
7. In a gas-engine, the combination, with a lifting gas-inlet valve, of an oscillating throttle-valve arranged behind the said inlet-valve, a sector upon the throttle-valve stem, a speed-governor operatively connected with the end of said sector, thereby controlling the admission of gas through the throttle-valve and permitting the said sector and lifting-valve to be actuated by the engine at periodic intervals, 50 a rocking lever operated periodically by the engine, and a push-piece upon the end of said lever and engaging with said sector, substantially as set forth.

In testimony whereof I affix my signature 60 in presence of two witnesses.

ARTHUR ROLLASON.
